MECHANISM FOR WINDING WIRE FABRIC
ONTO DRUMS

Noah S. Harter, Waukegan, Ill., assignor to Cyclone Fence Company, Waukegan, Ill., a corporation of Illinois

Application May 26, 1934, Serial No. 727,794

2 Claims. (Cl. 139—291)

The invention relates to improvements in weaving machines for weaving wire mesh fabric and has reference more particularly to novel mechanism for winding the woven fabric on to a drum 5 and for measuring the quantity so wound.

Looms for weaving wire fabric are provided with a hand drive which when actuated will produce movement of the fabric in the direction of feeding or in a rearward direction. The drive 10 is used to properly adjust the position of the woven fabric with respect to the oscillating shuttle bars and beater frame before starting the machine, and quite often the adjustment results in movement of the fabric backwards which 15 tends to unwind the woven material from the drum or roll on to which the same is wound. As it is necessary for most efficient operation of the weaving machine that the material be held under tension excessive unwinding of the same is to be 20 avoided.

An object of the invention is to provide apparatus for winding wire mesh fabric onto a drum and for measuring the quantity so wound as the operation proceeds, and which will be driven 25 from the weaving machine in a manner to permit adjustment without developing excessive slack in the woven material.

With these and various other objects in view, the invention may consist of certain novel features of construction and operation, as will be 30 more fully described and particularly pointed out in the specification, drawings and claims appended hereto.

In the drawings which illustrate an embodiment of the device and wherein like reference characters are used to designate like parts—

Figure 1 is an elevational view showing the winding and measuring mechanism of the invention in association with a conventional weaving 40 machine;

Figure 2 is a front elevational view of the winding and measuring mechanism;

Figure 3 is a top plan view of the same;

Figure 4 is a side elevational view of the mechanism; and

Figure 5 is a sectional view showing the ratchet connection provided in the drive to the winding mechanism.

The longitudinal wires 10 forming the warp 50 strands of the fabric are fed in any suitable manner to a weaving machine of conventional design, indicated by 12, which is not shown complete as the same forms no part of the present invention. The warp strands are interwoven by 55 the machine in the customary manner with weft

strands to form wire mesh fabric 14 which is passed under the machine and wound onto a drum by mechanism to be presently described. Frequent interruptions in the operation of the machine occur as the wires may break and the 5 bobbin periodically becomes exhausted and must be reloaded. Before starting the machine after these interruptions the material must be adjusted so that the weaving is resumed at the exact point where the same terminated, which 10 requires forward or rearward movement of the material. For the purpose the machines are provided with a hand drive including a horizontal shaft 15 extending along one side of the machine and having gear 16 fixedly secured to its 15 end for meshing with gear 17 secured to shaft 18 vertically positioned and journaled in bearings 19. The shaft carries a worm gear 20 meshing with gear 21 for rotating the friction rolls 22 which feed the longitudinal wires to the machine. Gear 23, also fixed to shaft 18, operates 20 through a plurality of gears to drive a spur gear 24, which in turn meshes with gear 25 fixedly secured to shaft 26. Said shaft is thus driven 25 from the hand drive 15, but at a considerably reduced speed.

The winding mechanism of the present invention is driven from the weaving machine through connection with shaft 26 and in order to prevent reverse rotation of the winding mechanism when the hand drive is rotated in a direction to feed the fabric backward through the weaving machine the invention provides ratchet mechanism between shafts 26 and 27. The same 30 consists, as shown in Figure 5, of a hub member 28 having a pawl 30 and a ratchet wheel 31 associated therewith and which is fixed so as to rotate with shaft 27. It will be seen from the above that shaft 27 has rotation in one direction only, that is, to cause winding of the material. Gears 32 operatively connect shaft 27 and the transverse shaft 33 (Figures 2 and 3) which carries at its opposite end a pulley 34. This latter shaft is journaled in the supporting frame structure 35 having uprights 36 and rotatably 35 mounts a roller 37 for contact with the woven fabric. The uprights 36 journal shaft 38 carrying drum 40 onto which the material is wound 40 to form a roll of the same. When the roll reaches the required size the shaft 38 can be released by 45 actuation of lever 41 to permit removal of the drum 40 from the apparatus. Another shaft and drum of similar construction can be journaled in the uprights and the operation again resumed or the roll of material can be immedi- 50 55

ately removed from the drum and the same replaced.

One end of shaft 38 has connection with pulley 42 which is driven from pulley 34 by the belt 43 held under proper tension by the idler roller 44. The belt provides a friction drive for the drum 40 which is driven from shaft 21 through the instrumentalities described. Provision is thus made for a considerable slippage between 10 the driving shaft and drum, which is necessary since the quantity of material wound on the drum per revolution increases as the diameter of the roll becomes larger, whereas, the quantity of woven material supplied by the machine is 15 fairly constant. By the structure described the material is wound on the drum and considerable tension is placed on the same to also maintain the woven fabric in the weaving machine under tension. As it may be necessary at times to 20 vary the tension on this fabric the amount of slippage occurring in the friction drive is made adjustable within limits through the provision of the idler roller 44 yieldingly held by coil spring 45 in contact with the belt 43 which thus 25 holds the same taut.

The uprights 35 journal shaft 46 which carries spaced arms 47 supporting a roller 48 having a knurled periphery and of considerable weight. The roller normally rests on the roll 30 of material wound on the drum 40 and serves to maintain the surface of the roll flat and free of kinks and wrinkles. The roll forms part of the counting mechanism as the same has rotation with the roll of material and which rotation is in proportion to the quantity of material wound on the drum. A counter 50 is 35 operatively connected through chains 51 with the roller 48 and is calibrated to measure the quantity of material wound on the drum. When it is necessary to remove the roll from the apparatus the roller 48 is lifted by handle 52 into an inoperative position, it being clear from the drawings that the same pivots on shaft 46 without disturbing the operative connections to the 40 counter 50.

It is to be understood that I do not wish to

be limited by the exact embodiment of the device shown, which is merely by way of illustration and not limitation, as various and other forms of the device will of course be apparent to those skilled in the art without departing from the spirit of the invention or the scope of the claims. 5

I claim:

1. The combination with a weaving machine of means located to the rear of said machine 10 for releasably and rotatably supporting a drum, said drum receiving the woven material which is wound on the drum to form a roll of material, connections operatively connecting the weaving machine with the drum including a friction drive 15 to permit slippage of the drum with respect to the machine, a roller having contact with the surface of the roll of material on the drum to maintain the same flat, means pivotally supporting the roller to permit bodily movement 20 of the same whereby the roller can be lifted out of contact with said roll of material, a measuring instrument, and connections from said roller to said measuring instrument for indicating the quantity of material wound on said 25 drum.

2. The combination with a weaving machine of means located to the rear of said machine for releasably and rotatably supporting a drum, said drum receiving the woven material which is 30 wound on the drum to form a roll of material, connections operatively connecting the weaving machine with the drum including a friction drive to permit slippage of the drum with respect to the machine, a weighted roller mounted for rotation and pivoted to the supporting frame to 35 permit bodily movement of the roller, said roller having contact with the roll of material on the drum to maintain the same flat and free of kinks and wrinkles, a measuring instrument and 40 roller, whereby said connections from said instrument to said roller drives the measuring instrument in proportion to the quantity of material wound on the drum. 45

CERTIFICATE OF CORRECTION.

Patent No. 2,076,778.

April 13, 1937.

NOAH S. HARTER.

It is hereby certified that error appears in the printed specification of the above numbered patent requiring correction as follows: Page 2, second column, lines 41-42, claim 2, strike out the words "connections from said instrument to said" and insert the same before "roller" in line 41; and that the said Letters Patent should be read with this correction therein that the same may conform to the record of the case in the Patent Office.

Signed and sealed this 6th day of July, A. D. 1937.

Henry Van Arsdale
